UNITED STATES PATENT OFFICE.

HENRY A. WEBBER, OF ROCKTON, ILLINOIS.

SNOW-PLOW.

SPECIFICATION forming part of Letters Patent No. 275,301, dated April 3, 1883.

Application filed December 2, 1882. (No model.)

To all whom it may concern:

Be it known that I, HENRY A. WEBBER, a citizen of the United States of America, residing at Rockton, in the county of Winnebago and State of Illinois, have invented certain new and useful Improvements in Snow-Plows, of which the following is a specification, reference being had therein to the accompanying drawings.

10 My invention has relation to snow-plows for clearing railroad-tracks of snow; and its object is to provide a device that will either clear off the surface snow, or, should the snow drift or pack to a greater height than the train, then 15 the machine tunnels a way through.

To these ends the novelty consists in the construction of the same, as will be hereinafter more fully described, and particularly pointed out in the claims.

20 In the accompanying drawings similar letters of reference indicate like parts of the invention.

Figure 1 is a side elevation of my improved plow. Fig. 2 is a front elevation of the same. 25 Fig. 3 is a top plan view of the plow with a portion of the upper shield removed, and Fig. 4 a detail view of one of the journals and bearings of the conveyers.

A is an ordinary platform-car, having wheels 30 *a a.*

B is an engine and boiler of the usual construction, mounted upon the car A.

C C are arms projecting from the forward end of the car A, and to these arms are secured the vertical hoods D D'. Across the 35 top of the vertical hoods D D' is mounted a longitudinal hood, E.

F is the base of the vertical hoods D D', and it forms the lower bearings of the convey- 40 ers G H, the shafts of which extend through so as to receive the gear-wheels I J, (not being shown,) while the upper ends of said conveyers G H are journaled in the brackets *e e*, secured to the upper ends of the hoods D D' and 45 forming part of the cover *h*, and to this top or cover *h* is secured the horizontal hood E. At both ends of the hood E is secured a bracket, *c*, which forms the bearing for the shaft *d* of the conveyer *d*. The conveyers may be either 50 of a single or double screw, and the vertical ones G H revolve from the center outward, while the horizontal conveyer *d* is provided

with a right-and-left-hand screw, which accom- 55 plishes the same result—viz., carries the snow from the center of the track outward on either side. Two vertical shafts, M N, are mounted in the rear of and parallel with the conveyers G H, and their lower ends are provided with gears *m n*, which mesh in the gears I J. The upper ends of these shafts are provided with angle-gears *m' n'*, which mesh in similar gears, *o o'*, secured to the shaft O, and on the center of this shaft is secured a large gear-wheel, P, which is operated by the driving-gear R, located on the crank-shaft S of the engine B. It will thus be seen that as the engine revolves the shaft O operates the angle-gears *m' n'* and *o o'* simultaneously, and through the medium of the shafts M N and gears *m n* the conveyers G H are rotated in 70 unison. A gear, T, on the center of the horizontal conveyer *d* engages with the gear-wheel P, so that the said conveyer is also driven at the same time and by the same means as the other two, G H. Thus the operation of the 75 engine causes the three conveyers to revolve, and as the car is forced forward they pack the snow on either side of the track.

Referring to Fig. 4, U is the shaft of one of the conveyers, which is preferably made hollow to combine strength with lightness, and the ends are fitted with bearings V, having recess *v*, and terminating in the journal *w*.

X is a collar, and is rigidly secured to the frame Y. This collar enters the recess *v*, and thus forms at once the support and bearing of the shaft U.

The front of the gear T on the conveyer *d* is protected by a cover, *t*, which prevents the snow from clogging the teeth of said gear.

The forward end, *f*, of the base *P* is inclined, so as to form a protector for the gears I J, and at the same time act as a shovel or scraper while the machine is being pushed forward.

Having thus described my invention, what I claim as new and useful, and desire to secure by Letters Patent of the United States, is—

1. The combination, with the conveyers G H, their hoods D D', and gears I J, of the gears *m n*, shafts M N, angle-gears *m' n'*, and the shaft O, provided with the gears *o o'* and P, substantially as set forth.

2. The combination, with the conveyers G H, their hoods D D', and their gears, of the

"right-and-left" conveyer *d*', hood *E*, and gears *T P*, substantially as set forth.

3. The hollow shaft *U* of the conveyer *G*, having bearing *V*, recess *v*, and journal *w*, in combination with the frame *Y*, having collar *X*, substantially as set forth.

In testimony whereof I affix my signature, in

presence of two witnesses, this 14th day of November, 1882.

HENRY A. WEBBER.
